UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,889, dated November 14, 1893.

Application filed October 7, 1893. Serial No. 487,510. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of ornamental scrolls of roccoco style forming connecting panels with groups of flowers and leaves arranged in said panels as represented in the accompanying drawing.

The border or upper portion of the design is separated from the hanging by a series of parallel lines and is formed of ornamental scrolls forming panels containing groups of flowers and leaves as shown.

What I claim is—

1. The design for wall paper herein shown and described.
2. In the design for wall paper the border herein shown and described.

Witness my hand this 2d day of October, 1893.

CHARLES BOOZE.
